R.C. FILTER WITH CAPACITANCE PRODUCED BY GRAIN BOUNDARY SEMICONDUCTOR

Wallace W. Lindemann, Minneapolis, and Rolf K. Mueller, St. Paul, Minn., assignors, by mesne assignments, to Litton Systems, Inc., Beverly Hills, Calif., a corporation of Maryland

Filed Jan. 6, 1961, Ser. No. 81,162

9 Claims. (Cl. 333—70)

This invention relates generally to RC networks and pertains more particularly to networks formed from semiconductive blocks having a grain boundary incorporated therein.

One important object of the present invention is to provide a miniaturized network that can be easily fabricated. While our invention will find utility in various situations, it can be pointed out that it possesses especial utility in the field of molecular electronics due to the extremely small size of the networks formed in accordance with the teachings of the instant invention. More specifically, it is contemplated that networks constructed in accordance with this invention will find use as RC filters and delay lines.

Considerable literature, both in periodical form and in the form of patents, is currently available with respect to the use of grain boundaries in semiconducting materials. As an example, see the book *Dislocations in Crystals* by W. T. Read, Jr. Consequently, it is not believed necessary to present the theory surrounding these grain boundaries. However, it may be quite helpful to point out that the resistance values of crystal grain boundaries such as those discussed in the noted publication can be made very high since they are very temperature dependent. On the other hand, the capacity values are temperature independent at temperatures below room temperature.

Other objects will be in part obvious, and in part pointed out more in detail hereinafter.

The invention accordingly consists in the features of construction, combination of elements and arrangement of parts which will be exemplified in the construction hereafter set forth and the scope of the application which will be indicated in the appended claims.

In the drawing:

FIGURE 1 illustrates one embodiment that the invention may assume;

FIG. 2 represents a somewhat modified version of FIGURE 1, it being planned that the embodiment of FIG. 2 will be utilized in substantially the same situations as the embodiment of FIGURE 1;

FIG. 3 is a schematic diagram representing the equivalent circuit of both FIGURES 1 and 2;

FIG. 4 is a different embodiment from the embodiments pictured in FIGURES 1 and 2;

FIG. 5 is still a different embodiment but possessing the same operating characteristics as the embodiment set forth in FIG. 4, and

FIG. 6 is a schematic diagram representing the equivalent circuit of the embodiments of FIGURES 4 and 5.

Referring first to FIGURE 1, it will be observed that a block of semiconductive material labelled 10 has been pictured. One side of the block 10 has attached thereto a resistive contact 12, and the side opposite to this particular side has a pair of spaced resistive contacts 14, 16 secured thereto. A grain boundary 18 extends from one end of the block to the other in a generally parallel direction to the sides or faces to which the contacts 12, 14, and 16 are attached. Through well known diffusion techniques, an impurity is introduced into the semiconductive material to produce a doped region 20 on one side of

2

the grain boundary 18 and, similarly, a doped region 22 is provided on the other side. The semiconductor having the grain boundary is prepared by growing a bicrystal from precisely oriented double seeds. A semiconductor block is cut from this bicrystal. The doped region 20 and 22 near the grain boundary are produced by uniformly introducing an *n* or *p* type impurity into the crystal during the growing process. As more impurity is introduced, the doped region becomes larger and leaves less intrinsic material thus lowering the total resistance (see FIG. 1.) In the embodiment now being described, a region of intrinsic or undoped material remains between the region 22 and the contacts 14, 16, this pair of contacts actually being affixed to the region 24 in the present instance. The intrinsic layer is established by making use of non-uniform impurity distributions in the bicrystal block. For the purpose of assisting the reader in orienting himself with respect to both FIGURES 2 and 3 a terminal 26 has been shown in association with the contact 14 and a terminal 28 has been shown in association with the contact 12. These terminals can be considered the input terminals to the network constituting FIGURE 1. On the other hand, a terminal 30 is connected to the contact 16 and a similar terminal 32 is connected to the previously mentioned resistive contact 12, the terminals 30, 32 serving as output terminals in the illustrative situation. The use of these terminals will, however, be better understood when the equivalent circuit depicted in FIG. 3 is described.

Considering now the embodiment of FIGURE 2, it should be explained at the outset that this embodiment is quite similar to that of FIGURE 1. Therefore, it will be helpful to utilize the same reference numerals where there is a direct similarity, but distinguishing these reference numerals by the suffix *a*. The main difference between the embodiment now being described and the previously referred to embodiment resides in the fact that the alloyed contacts 14a and 16a are located at opposite ends of the grain boundary 18a, whereas in the previous embodiment these contacts were resistive and were located on the intrinsic region 24. It will be understood that a grain boundary, such as that with which we are currently dealing, has both resistance and capacitance incorporated thereto. These resistance and capacitance characteristics are explained in more complete technical detail in two articles published by Rolf K. Mueller. The first, *Capacitance and Barrier Height in Grain Boundaries*, published April 1959 in volume 30, No. 4, pages 546-550 of the *Journal of Applied Physics*, deals with the capacitance characteristics and the second, *Captured Diameter of Dislocations in Low Angle Grain Boundaries in Germanium*, published in the *Journal of Physics and Chemistry of Solids*, Pergamon Press 1959, volume 8, pages 157-161, deals with resistance characteristics. Thus, whereas the intrinsic region 24 of FIGURE 1 produced the resistance needed in the network, the present embodiment utilizes the inherent resistance of the grain boundary itself.

Having described both FIGURES 1 and 2, it will now be of assistance to refer briefly to FIG. 3. In this figure, which is the equivalent circuit of what has been disclosed in FIGURES 1 and 2, the resistance has been denoted by the reference numeral 34, such resistance extending between the terminals 26 and 30. As indicated immediately above, the resistance corresponding to that of 34 is provided by the intrinsic region 24 in FIGURE 1 and by the grain boundary itself in FIG. 2. Distributed capacitance exists between the resistance 34 and the terminals 28, 32. This distributed capacitance has been designated by several capacitors 36. In the embodiment of FIGURE 1, the capacitance is provided by the grain

boundary 18, and the grain boundary 18a of FIG. 2 supplies the capacitance in the second embodiment. In either situation, that is, in using the embodiment of FIGURE 1 or the embodiment of FIG. 2, the cut off frequency of the network when used as a filter can be varied by applying a negative bias to the boundary 18 or 18a.

Turning now to the embodiment of FIG. 4, here again certain similarities exist and these similarities have been highlighted by utilizing the same reference numerals as with respect to FIGURES 1 and 2, the suffix *b* being employed as the distinguishing medium. Actually, it will be discerned that the basic difference between the embodiment now being referred to and that of FIGURE 1 resides in the existence of a second intrinsic or undoped region labelled 38. In this situation, the resistive contact 12b is attached directly to the layer or region 38.

With respect to FIG. 5, the suffix *c* has been utilized. This embodiment corresponds most closely to that of FIG. 2 and it will be observed that the intrinsic layer or region 38c is the distinguishing characteristic. This region 38c corresponds, of course, to the region 38 of FIG. 4. At any rate, it is readily apparent that the resistive contact 12c of FIG. 5 is attached directly to the region 38c, whereas in FIG. 2 the corresponding contact was affixed to the doped region 20a.

While the difference in result is believed manifest from what has been presented in the way of explanation with regard to FIGS. 4 and 5, nonetheless attention is called at this time to FIG. 6. As with FIG. 3, FIG. 6 is presented in order to show the equivalent circuitry of FIGURES 4 and 5. The resistance 34 is the same as that of FIG. 3, and the capacitance is the same also. Consequently the capacitors appearing in FIG. 6 have been given the reference numeral 36. However, it will be noted that additional resistance in the form of a resistor 40 appears in FIG. 6 and not in FIG. 3. The resistance so derived stems from the use of the intrinsic region 38 of FIG. 4 and the similar region 38c of FIG. 5. It will be recognized that the filter of FIG. 6 is what may succinctly be described as a distributed constant bridged T filter. Here again, the frequency of the pass band can be adjusted by modifying a bias voltage applied to the boundary.

RC delay lines can be also readily devised with the configurations that have been pictured herein.

As many changes could be made in the above construction and many apparently widely different embodiments of this invention could be made without departing from the scope thereof, it is intended that all matter contained in the description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

What is claimed:

1. An RC network comprising a block of semiconductive material, a first contact at one location on said block and a pair of spaced contacts at different locations on said block, said block including a region of doped material provided with contacting crystals having different spatial orientations, said contacting crystals defining a grain boundary between said first contact and said pair of contacts, said region being between said first contact and said pair of contacts.

2. An RC network in accordance with claim 1 in which said block includes a layer of intrinsic material between said pair of contacts and said grain boundary.

3. An RC network in accordance with claim 1 including a region of intrinsic material between said first contact and said region of doped material.

4. An RC network in accordance with claim 1 in which said pair of contacts are alloyed and located on said grain boundary.

5. An RC network in accordance with claim 2 in which said pair of contacts are resistive and located on said intrinsic material.

6. An RC network in accordance with claim 2 in which said block includes a second region of intrinsic material, said regions of intrinsic material being on opposite sides of said region of doped material with said first contact being resistive and on one of said intrinsic regions and said pair of contacts being alloyed and on the other of said intrinsic regions.

7. An RC filter network comprising a block of semiconductive material having a doped region provided with contacting crystals having different spatial orientations, said contacting crystals defining a crystal grain boundary having a predetermined capacitance, a layer of intrinsic material contacting said doped region for providing an electrically resistive region, a pair of terminals connected to said layer in spaced relationship to provide a predetermined resistance path between the terminals through said layer, and a contact on said block across said boundary from said terminals for providing a capacitive electrical path through said block.

8. An RC network comprising a block of semiconductive material having a doped region provided with contacting crystals having different spatial orientations, said contacting crystals defining a crystal grain boundary in said doped region having a predetermined capacitance, a first layer of intrinsic material contacting said doped region at the first side for providing an electrically resistive region, a second layer of intrinsic material contacting said doped region at a second side for providing an electrically resistive region, a pair of terminals connected to said first layer in spaced relationship to provide a predetermined resistance path between said pair of terminals through said first layer, and a contact on said second layer across said boundary from said pair of terminals for providing a series capacitive and resistive electrical path through said block.

9. An RC network comprising a block of semiconductive material, a first resistive contact at one location on said block, and a pair of alloyed contacts on opposite sides of said block, said block including a region of doped material spaced from said first resistive contact and provided with contacting crystals having different spatial orientations, said contacting crystals defining a grain boundary extending between said pair of alloyed contacts, with said alloyed contacts located on said grain boundary, said blocking including a region of intrinsic material between said first resistive contact and said region of doped material, said region of intrinsic material being in contact with said first resistive contact.
